WILLIAM M. BAGER AND WERNER LEHMAN, OF SOUTH MILWAUKEE, WISCONSIN, AS
SIGNORS TO BUCYRUS-ERIE COMPANY, OF SOUTH MILWAUKEE, WISCONSIN, A COR-
PORATION OF DELAWARE

EXCAVATING MACHINERY

Application filed January 4, 1926. Serial No. 79,162.

Our invention relates to new and useful improvements in excavating machinery, particularly of the types known as revolving power-shovels, and more particularly of that 5 type of revolving power-shovel designed primarily for mining-work, as that work is of a nature to necessitate an unusually compact, sturdy and mobile construction.

It is one object of our invention to provide 10 a novel and strong type of roller track. Heretofore two methods of constructing this track have been used, both of which have inherent defects. One of these methods uses as track a machined face on the base casting. 15 As the base in its entirety must be cast of one metal, the dilemma is presented of making the whole casting of metal hard enough to provide a proper track face, with consequent difficulty of machining, or of making the 20 whole casting of ductile metal in which case the track face wears excessively. This scheme precludes easy replacement of wearing surfaces. The second method is to mount a curved rail upon the base casting. This is 25 subject to the defect that the web of the rail, being fatigued by excessive strain and shock, will crack and break after relatively short use. We have avoided both classes of defects by machining a circular groove in both the 30 upper and lower frames, which are both of the softer metal usually employed, and then spot-welding or otherwise securing in each of these grooves a machined ring of harder metal to furnish a bearing for the rollers. 35 Such securing of the ring permits replacement without affecting the large base and frame castings and involves a minimum of expense and labor.

Our revolving frame is made of two castings rigidly pin-connected together, the line 40 of division being transverse of the frame. While this frame could be cast in one piece, it would tax shop facilities to machine such 45 a large member. We have thus provided a construction next best to a unitary casting, and much superior to the usual trussed structure consisting of two side beams and a number of cross beams, all connected by a multiplicity of bolts which are likely to work loose,

thereby causing loss of time for constant overhauling.

One object of our division of the revolving frame into two castings is to supply an interchangeable rear end for this frame. Accord- 55 ing as the power to actuate the prime mover is steam, gasoline, electric or other power, certain radical changes, besides that of the prime mover itself, become necessary. It is obvious, for instance, that a steam boiler, re- 60 quiring ash pit, bunker space, etc., necessitates a different base than an electric, gasoline or Diesel motor. In order to avoid the change of the whole revolving base, we have placed the power-generating plant and its 65 more immediate accessories upon the rear portion of the frame, keeping the machinery elements which are independent of the character of the source of power on the forward, permanent portion. This rear portion is pin- 70 connected to the forward portion. This division of the revolving frame also allows the possibility of shipping this frame in two 75 pieces, in case it is inconvenient or impossible to ship it as a unit.

A further object of our invention is to provide a novel form of creeping traction mounting. The advantages of the approved form of mounting in use up to the present are set forth in Letters Patent No. 1,485,945, 80 issued March 4, 1925, to the first named of the applicants in this present case, wherein Figure 6 shows the cantilever brackets usually employed by us to carry the stub-axles of the rollers and tumblers, as being separately and 85 rigidly mounted upon the lower frame. However, as the excavator is increased in size, the difficulties encountered will begin to offset the advantages. The base becomes unwieldy, too large for shipment with rollers and tumblers in place, and subject to excessive strain on the cantilever brackets. By assembling our creeping traction unit upon stub-axles rigidly attached to a side frame, which 90 side frame is rigidly attached to the main base, we have eliminated the disadvantages 95 enumerated above. It is therefore possible for us to ship each traction unit completely assembled, thereby retaining all the advantages set forth in the said patent.

It is to be noted that our construction of the creeping traction unit and our method of mounting it, allow easy access to all parts of the unit without demounting or disassembling.

We have furthermore provided a novel lock or brake for the creeping traction units, that is easily placed in or out of action and which when in use, effectively prevents the reaction to the digging operations from moving the excavator as a whole back from its operating position.

A further object of our invention is to provide a novel and non-binding means for maintaining the tread-belts taut.

A still further object of our invention is to provide a combined wobbler and clutch disconnectably joining the propelling machinery to the power source.

Other advantages of our new and improved excavating machinery will be evident to those skilled in the art, and need not be herein more specifically set forth.

The invention consists in the novel parts, and in the combinations and arrangements thereof, which are defined in the appended claims; and of which one embodiment is exemplified in the accompanying drawings, which are hereinafter particularly described and explained.

Throughout the description the same reference number is applied to the same member or to similar members.

Figure 1 is a more or less conventionalized side elevation of the entire excavator, illustrating however in sufficient detail the rear-end construction claimed.

Figure 2 is a plan view of the base and of the creeping traction mounting, the right half of the drawing being partly in section.

Figure 3 is a side elevation of one creeping traction unit (part conventionalized), of the base, and of the front part of the revolving frame, the front portion being in section to illustrate the rollers and roller-tracks.

Figure 4 is a detailed vertical, longitudinal section along the line 4-4 in Figure 2.

Figure 5 is an enlarged view of that portion of Figure 3 which shows the roller and roller-tracks in section.

Figure 6 shows an alternative form for the take-up device shown in Figure 4.

Figure 7 is an elevational view, partly in section, of two clutch members, showing the key or chock in position to lock the traction unit against movement.

Referring to the drawings, it will be seen that 1 represents the main base casting of a turntable, revolvably mounted on casting 2, which in turn is supported on two creeping-traction units, one of which is shown conventionally as 3 in Figure 1.

Casting 1 carries the hoist winch 4, the swing machinery 5, the A-frame 6 and the boom 7. The boom is supported from the

A-frame by back-braces 8. A dipper 9 mounted on handles 10, is arranged to swing about, and reciprocate with respect to, a pivot 11 on the boom; the swinging of the dipper being accomplished by the hoist-cable 12, which passes over the boom-point sheave 13, and is actuated by the winch 4; and the reciprocating being accomplished by the boom-engine 14, acting in the usual manner, which need not be more particularly described.

All the foregoing is common to many types of power-shovels, and is more or less conventionally shown in Figure 1.

Casting 1 carries at each side, at the rear thereof, two lugs 15, by means of which is attached and supported the rear-end casting 16, which carries the steam boiler 17 and its appurtenances. Braces 18 connect the A-frame 6 to the rear-end casting, but do not contribute, except incidentally, to the support of the rear-end casting.

Turning now to Figure 3, we find mounted on casting 2, a circular rack-member 19, having an internally-projecting annular web 20, which rests on and is bolted to the flat, upper portion 21 of the casting 2.

Projecting downwardly through the casting 1, is a vertical swing shaft 22, having at its top end a bevel-gear 23, driven by the swing-machinery 5, and at its lower end a pinion 24, engaging the rack 19 for revolving the turntable.

In the bottom surface of casting 1 is machined an annular groove 25, in which is inserted a wear-resisting ring 26, which is preferably welded in place. A similar ring 27 is inserted in a similar groove 28 in the web 20 of the rack 19.

The ring 26 travels on a series of rollers 29 which in turn travel on ring 27. The rollers are spaced apart from each other by inner roller-ring 30 and outer roller-ring 31.

This construction constitutes a great improvement over the current practice of machining the roller paths on the non-wear-resisting metal of the casting 1 and the web 20.

A detailed cross-section of the grooves 25 and 28, the rings 26 and 27 and the rollers 29 is shown in Figure 5, on the same sheet with Figure 3.

Referring to Figure 2, and more particularly to the right hand portion, it is seen that the rollers 32 are rotatably mounted on stub-shafts 33, said stub-shafts being rigidly mounted in the side-frame 34 of the creeping traction unit. This side-frame 34 bears integral therewith an upper plate 35. Upon this upper plate there rests, being bolted thereto by bolts 36, the lower plate 37 of the casting shown as 2 in Figure 1. The upper portion of casting 2 is the beforementioned flat portion 21, (as shown in Figures 1 and 5,) upon which rests the annular web 20 of the rack member 19. Figure 2 shows the radial members 38 which connect the outer por-

tions of casting 2 with the central bearing sleeve 38^a. The upper portion 21 and the lower portion 37 of this casting are connected by webs 39.

5 The non-driving tumbler 40 is rotatably carried on the cylindrical end of the square load-supporting non-rotatable stub-axle 41, which axle projects inwardly from the side frame 34 a relatively small distance, its end abutting a beam 42 of similar square cross-section; the abutting ends of 41 and 42 being joined together by any suitable means that will give rigidity while at the same time allowing easy separation for convenience of shipment. Such a means may, for instance, 15 be a separate sleeve (not shown), into which the abutting ends of 41 and 42 are inserted and to which both are bolted. Or the element 42 may itself constitute such a sleeve, 20 being socketed at its ends for the reception of the end of the stub-axle 41.

The stub-axle 41 is movable longitudinally with respect to the creeping traction unit, by means of the yoke 43 and the take-up bolts 44. 25 This construction, which is shown in detail in Figure 4, is for the purpose of providing an efficient means for keeping the traction-belt taut, by means of the nuts 45. An alternative form of this take-up device is shown 30 in Figure 6, the bolt-holes being made of substantially larger size than the bolts 44, in order that the thread of the bolts shall not be worn by contact with the sides of the bolt-holes, and the nuts 45^a being provided with a 35 cylindrical guide-collar 45^b which projects into the bolt-hole for the purpose of centering the bolt in the hole.

When the beam 42 is removed, the stub-axle 41 is held only by two bolts which are 40 disposed in a vertical plane longitudinal to the traction unit, and is therefore capable of some amount of horizontal rotation. As such rotation would loosen the tread-belt and thus make trouble in shipment, the stub-axle 41 is in that case secured in position by the 45 insertion of temporary chocks (not shown).

Power for moving the excavator is conveyed from the machinery shown in Figure 1 through the rotation of the vertical shaft 50 (not shown) which is central to the frame 2 and to the rack 19. The lower end of this shaft carries rigidly mounted thereon a bevel pinion (not shown) which meshes with the bevel gear 46. This bevel gear is rigidly 55 mounted on a shaft 47, which bears a bevel pinion 48 rigidly mounted on its other end. Meshing with the pinion 48 is a bevel gear 49 mounted on the drive-shaft 50. This drive-shaft 50 is rotatably carried in two bearings 60, 61, which are rigidly mounted on the lower frame 2, and are widely separated in order to provide a rigid and true alignment of said shaft 50.

Each end of said shaft 50 bears non-rotatably mounted thereon an inner male clutch

member 52, aligned with a similar outer male clutch member 53 which latter is rigidly mounted on a stub-shaft 54. This stub-shaft is rotatably held in relatively widely separated bearings 55, 55, which are rigidly borne 70 by the side frames 34, and therefore hold the stub-shaft in true alignment with the drive shaft 50.

Slidable, so as to engage only with the outer male clutch member 53, or to engage 75 both male clutch members 52 and 53 is a female clutch member, or clutch ring 56, which serves the double purpose of wobbler clutch and coupling. This clutch ring 56 is actuated in any convenient manner.

Between the two bearings 55, 55, the shaft 54 is squared and carries a pinion 57, which meshes with a gear 58. Said gear 58 is carried on a squared portion of the driving axle 59. The driving axle is journaled in bearings 60, rigidly carried by the creeping traction side frame 34, and carries at its outer end, which is also squared, the driving tumbler 61, by means of which the tread-belt 62, which surrounds the tumblers 40 and 61 and 80 the rollers 32, is driven.

Having now described the method of conveying the power from the prime mover to each tread belt, it will be seen that, according as the clutch ring 56 on either side engages 95 only the inner male clutch member 52, or engages both male clutch members 52 and 53, the tread-belt on that side will idle or will be driven.

A removable gear cover 63, shown at the left in Figure 2, is bolted over the bearings and pinions on stub-shaft 54 and on tumbler shaft 59. The gear case carries a projection 64 which is sufficiently elevated above the outer clutch member 53 to allow free sliding of the clutch-ring 56 to all its required positions. This projection is provided with a vertically elongated socket of rectangular horizontal cross-section, which serves as a key-way. A key or chock, as shown in Figure 7, or any convenient substitute, whose cross-section is similar to that of the said socket, is provided for insertion into the socket; the lower end of said key being of the proper size and shape to fit into the grooves between the teeth of the outer male clutch member 53. This key may conveniently be connected by a chain to some adjacent portion of the structure. When inserted into the socket and into a groove of the clutch member 53, the key effectually prevents any rotation of said clutch member and therefore of the traction unit. The excavator is therefore held immovably braked in spite of excessively heavy thrust at the digging end. 125 It will be evident that the chock cannot be inserted when the ring 56 is in clutching position.

Having now particularly described and illustrated one form of our improved excavat-

ing machinery, we wish to be understood as not limiting ourselves to the particular form exemplified, but rather as availing ourselves of all equivalents.

5. Claims to the turntable ring feature shown in this application are included in our copending application, Serial No. 177,396, filed March 22, 1927.

10. Claims to the two-part cast base feature shown in this application are included in our copending application, Serial No. 177,397, filed March 22, 1927.

15. Claims to the creeping-traction belt take-up feature shown in this application are included in our copending application, Serial No. 30,552, filed May 15, 1925.

We claim:

20. 1. In a machine of the class described, the combination of: a base; a power-source mounted thereon; two removable creeping-traction units supporting the base; two rigid frames, one in each traction unit; stub-axles rigidly mounted on, and projecting outwardly from, the frame of each traction unit; load-supporting rollers, one journaled on each stub-axle of each traction unit; two non-rotatable axles, one in each traction unit, each such axle being mounted for longitudinal adjustment with respect to the frame of 25 its traction unit; two non-driving tumblers, one mounted on the non-rotatable axle of each traction unit; two driving axles, one mounted in each traction unit; two driving tumblers, one mounted on each driving axle; 30 two gear reductions, one being for each driving axle; two completely disconectible means, one drivably connecting each gear-reduction to the power source on the main frame; two creeping traction tread-belts, one disposed around the tumblers and rollers of each traction unit; and disconnectible means holding the two non-rotatable axles in rigid relation to each other.

45. 2. In a machine of the class described, the combination of: a base; a power-source mounted thereon; and two self-contained creeping-traction units rigidly supporting the base, and readily removable therefrom as an intact unit; each unit being comprised 50 as follows, namely: a rigid frame; stub-axles thereon, projecting outwardly beyond said frame; a load-supporting roller journaled on each stub-axle; a load-supporting axle adjustable longitudinally of said frame; a 55 tumbler mounted on said axle; a driving-axle; a driving-tumbler mounted on said driving-axle; means drivably connecting said driving-axle to the power-source on the main frame; and a creeping-traction tread-belt disposed around said tumblers and rollers.

60. 3. In a machine of the class described, the combination of: a base; a power-source mounted thereon; a plurality of removable creeping-traction units rigidly supporting 65 the base; a shaft mounted on said base and

driven by said power-source; a shaft mounted on one of said creeping-traction units and driving said unit; and a clutch, two members of which are respectively carried by said shafts; said members being held in operative 70 relation to each other by the rigidity of the relation between the base and the creeping-traction unit.

4. In a machine of the class described, the combination of: a base; a power-source 75 mounted thereon; a plurality of removable creeping-traction units rigidly supporting the base; a shaft mounted on said base and driven by said power-source; a shaft mounted on one of said creeping-traction units and 80 driving said unit; and a clutch, consisting of two members of one sex and one member of the other sex, the two members of the same sex being respectively carried by said shafts, and the one member of the other sex serving 85 as a wobbler driving connection between said two shafts, said members being held in operative relation to each other by the rigidity 90 of the relation between the base and the creeping traction unit.

5. In a machine of the class described: two load-supporting tumblers both rotating in one plane; a creeping-traction belt disposed about said tumblers; an axle for each of said tumblers, one axle being held against motion 95 longitudinally of said belt and the other being slidable longitudinally of said belt; a yoke bearing against that side of the slidable axle which lies toward the held axle, one end of said yoke being above and the other below 100 the slidable axle; and means for moving each end of said yoke independently of the other end of said yoke, such motion being longitudinal of said belt and for the purpose of controlling the tension in said belt.

105. 6. In a machine of the class described: two load-supporting tumblers both rotating in one plane; a creeping-traction belt disposed about said tumblers; an axle for each of said tumblers; one axle being held against motion 110 longitudinally of said belt, and the other being slidable longitudinally of said belt; a yoke pivoted on the slidable axle, one end of said yoke being above and the other below the slidable axle; and two bolts, one for moving each end of said yoke independently of the other end of said yoke, such motion being longitudinal of said belt and for the purpose 115 of controlling the tension in said belt.

120 WILLIAM M. BAGER. 120
WERNER LEHMAN.
